UNITED STATES PATENT OFFICE.

FRANK M. VAWTER, OF BENTON HARBOR, MICHIGAN, ASSIGNOR TO BAKER-VAWTER COMPANY, OF BENTON HARBOR, MICHIGAN, A CORPORATION OF MICHIGAN.

GUIDE-CARD.

1,259,322.

Specification of Letters Patent. Patented Mar. 12, 1918.

Application filed October 2, 1917. Serial No. 194,374.

To all whom it may concern:

Be it known that I, FRANK M. VAWTER, a citizen of the United States, residing at Benton Harbor, Berrien county, Michigan, 5 have invented new and useful Improvements in Guide-Cards, of which the following is a specification.

My invention, as will be understood from the description and explanation hereinafter given, is particularly adapted for application to the index or guide-cards of vertical filing systems now in extensive use for many purposes, although it is also capable of being used upon the indexes of books, particularly those of a heavy and substantial character, and in other cases where sheets or cards are provided with projecting tabs whereby the sheets are adapted to be turned or separated manually. I have therefore 10 illustrated and will describe my invention with reference to a set of guide cards such as are commonly used for vertical filing or in card indexes, but without intention of limiting my invention narrowly thereto. 15 The object of my invention is to provide a projecting manipulating tab which shall be simple, strong, durable, cheap to manufacture and attractive in appearance, and in general, shall fulfil, in a maximum degree, all the requirements of such tabs. To 20 this end I have devised the novel structure hereinafter described, and my invention consists in the construction, arrangement and character of the different parts of such 25 structure, the essential elements of which are recited in the appended claims.

Of the drawing Figure 1 is a fragmentary face view of the tab and adjacent portion of a guide card, the tab being shown somewhat 30 larger in size than those in common use; Fig. 2 is a sectional view taken centrally of the sheet and looking in the same direction; Fig. 3 is an enlarged section on the line 3-3 of Fig. 1; and Fig. 4 is a view of the 35 top portions of a set of guide cards to which my invention is shown applied.

The same reference characters indicate the same parts in all the figures of the drawing.

It has heretofore been proposed to reinforce tabs of guide cards such as those to 40 which my invention relates with a facing of sheet celluloid folded to extend over and

cover the opposite faces of the tab, but in practice it is found that while such a reinforcement is strong, sanitary and attractive in appearance, it is subject to the disadvantage of being liable to crack along the folded line at the edge of the card. As illustrated, my invention consists in interposing, at the 45 edge of the tab, marked A, and along the folding line b of the sheet of celluloid B, a length of round metal wire C of a diameter approximately equal to the thickness of the card, the celluloid and wire being cemented 55 to the card by any suitable cement. The wire length affords a smooth, hard, rounded surface around which the celluloid facing curves and by which it is rigidly supported 60 in such manner that it cannot be crushed 65 and sharply creased, either in the manufacture of the tab or subsequently, and is stiffened so that in handling the card the edge of the card is restrained against bending 70 and flexing, with the result that the 75 celluloid will not crack along the edge as in the case of the prior form of construction mentioned.

It is obvious that while my invention is particularly valuable as applied to a facing 80 or reinforcement of sheet celluloid, it may also be used to advantage with other sheet material, as paper, or cloth, if desired, and will give increased strength and durability 85 to such structures. It is further obvious that it may be applied to guide or index tabs wherever used, whether on the guide cards of vertical filing systems, or elsewhere.

I claim:

1. A guide card for vertical filing systems 90 and the like and formed with a projecting tab portion, said card having a folded sheet celluloid facing cemented to the opposite faces of said tab portion and also having a length of round wire interposed between 95 said facing and the edge of said tab portion along the folding line of the facing.

2. A guide card for vertical filing systems 100 and the like and formed with a projecting tab portion, said card having a folded facing of sheet material cemented to the opposite faces of said tab portion and also having a length of wire interposed between said facing and the edge of said tab portion along the folding line of the facing.

FRANK M. VAWTER.
